STARTING RELAY CIRCUIT FOR SINGLE PHASE MOTORS

Robert H. Rech, Milwaukee, Wis., assignor to
 A. O. Smith Corporation, Milwaukee, Wis., a
 corporation of New York

Application April 5, 1950, Serial No. 154,149

7 Claims. (Cl. 318—221)

1

This invention relates to relay circuits for controlling the energization of the starting windings of single phase motors.

In single phase motors of the type wherein a relay is used to open the starting circuit of the motor as running speed is approached, it is customary to connect the relay coil either across the series combination of the starting winding and the relay contacts or across the starting winding alone. The former of these alternatives is undesirable in many applications because a line derived voltage is impressed across the relay coil during the entire period of motor operation and the relay contacts, once open, will not close again and re-energize the starting circuit even though the load is sufficiently great to slow the motor to a very low rate of speed.

The latter alternative, that of connecting the relay coil across the starting winding alone, has also been found to be disadvantageous in that the relay contacts tend to rapidly open and close before they finally remain open as a result of the increasing motor speed. This fluttering or chattering of the contacts causes them to heat excessively and possibly to weld together and maintain the starting winding in the line circuit while the motor is operating at running speed. Since a starting winding is normally not rated for use over a long period of time, the retention of the starting winding in the line circuit may result in serious overheating.

The principal object of the invention is to provide a simple and inexpensive means for preventing the above described relay contact fluttering, with consequent elimination of the danger of overheating the starting winding.

Another object of the invention is to promote positive action of the relay contacts and thus to reduce the arcing therebetween and lengthen the life thereof.

Another object of the invention is to increase the differential between the motor speed at which the relay contacts open and the speed at which they close, so that the contacts will have the benefit of a relatively long cooling interval in the event of cyclic operation of the motor.

The circuit, in general, comprises a relay coil connected across the starting winding of a single phase motor and having contacts arranged to break the starting circuit of the motor as running speed is approached, a half wave rectifier connected in series with the relay coil to rectify the current flowing thereto, and a filter capacitor shunted across the coil to maintain the energization thereof during the interval when current

2

flow is blocked by the rectifier. In a separate embodiment of the invention, wherein the filter capacitor is eliminated, one side of the relay coil is tapped to the center of the starting winding and the other side thereof is connected through separate leads and rectifiers to opposite ends of said winding, so that the energization of the coil is maintained in one direction by half wave current pulses from the respective rectifiers.

Other objects and advantages of the invention will be set forth more fully in the following description of embodiments of the invention illustrated in the accompanying drawings.

In the drawings:

Figure 1 is a schematic wiring diagram of an embodiment wherein a rectifier and filter capacitor are used in combination with a capacitor start single phase induction motor; and

Fig. 2 is a diagram of another embodiment of the invention, illustrating the use of two rectifiers instead of a rectifier and a filter capacitor.

The invention is illustrated in the drawings as applied to a capacitor start single phase induction motor adapted to be energized through lines 1 and 2 and a line switch 3 by a suitable source of 110 volt single phase alternating current supply. The motor comprises, in addition to a squirrel cage rotor, not shown, a running circuit which is operative during the entire period when the switch 3 is closed and a starting circuit which is only operative to create starting and low speed torque and is consequently disconnected as running speed is approached.

The running circuit of the motor includes a running winding 4 which is connected across lines 1 and 2 and is shown for purposes of illustration as split into a pair of series arranged segments 5 and 6.

The starting circuit comprises a starting winding 7 connected in series combination with a phase shifting starting capacitor 8 across one of the segments 5 of the running winding 4. The winding 7 and capacitor 8 could also be connected, without changing the invention, across the entire run winding 4, in which case the splitting of the winding 4 into the segments 5 and 6 would be unnecessary.

Referring to Fig. 1, the starting circuit of the motor is broken, as running speed is approached, by means of a relay 9 having a coil 10 and a pair of normally closed contacts 11. The coil 10 is connected in parallel with the starting winding 7 and is consequently subject to substantially the same voltages. The contacts 11, which may

be arranged at any point in the starting circuit, are shown as located between the starting winding 7 and the capacitor 8.

When the relay contacts 11 are closed, the voltage across the coil 10 is the resultant of the voltage derived from the lines 1 and 2 through the starting capacitor 8 and the voltage induced in the starting winding 7 from the rotor. The opening of the contacts 11 reduces the voltage in the coil 10 to the amount of the induced voltage alone and may operate, because of the inherent relay characteristics next to be described, to cause the contacts 11 to reclose and initiate a fluttering action.

As the result of variations in the length of the air gap between the armature and core of the relay 9, the coil voltage necessary to actuate the contacts 11 varies according to whether the contacts are initially in a closed, open, or intermediate position. For example, the design of the relay 9 may be such that a 150 volt "pick-up" or contact opening voltage is required to create sufficient magnetism to overcome the large initial air gap, whereas only 45 volts is necessary, once the armature is sealed against the coil 10, to prevent the relay from "dropping out" and allowing the contacts 11 to close. When the air gap has been only partially closed, as is the case immediately after the relay picks up and the contacts 11 open a slight distance, approximately 70 volts will be required to "seal in" the armature and open the contacts the remainder of the way.

Under the above illustration, wherein the relay 9 is assumed to have a 150 volt pick-up voltage and a 70 volt seal-in voltage, the contacts 11 will not be held open after pick up unless the induced voltage in the starting winding 7 is at least 70 volts when the resultant of the induced voltage and the line derived voltage is 150 volts. This is because the voltage across the winding 7 and the relay coil 10 is instantly reduced, upon the opening of the contacts 11, from 150 volts to the value of the induced voltage alone. Assuming that the induced voltage is less than 70 volts at the instant when the resultant of the induced and line derived voltages is the 150 volt pick-up value, the relay 9 will not seal in after the contacts 11 have opened but instead will allow the contacts to close and cause the voltage across the relay coil to be increased to 150 volts again. The contacts 11 will then reopen and the cycle will be repeated, in a rapid fluttering or chattering action, until the motor speed has increased sufficiently to create an induced voltage in excess of 70 volts.

The described fluttering, which occurs in the majority of relays used with single phase motors as herein described, has been a cause of excessive heating of the contacts 11 and excessive wear thereon. In certain cases, the heating may be sufficient to weld the contacts 11 together and maintain the flow of line current through the starting winding while the motor is operating at running speed, which in turn may cause the winding 7 to overheat and burn out.

According to the invention, a half wave rectifier 12 is connected in series with the relay coil 10, so that the current flowing to the coil 10 from the winding 7 or the lines 1 and 2 takes the form of a unidirectional pulse which flows during half of each wave cycle. The energization of the coil 10 is maintained during the other half of each wave cycle by a filter capacitor 13 which is arranged in parallel with the coil 10 to discharge

current therethrough in the same direction as the current flow from the rectifier 12.

The rectifier 12 is preferably of the barrier type, comprising discs coated with selenium, copper oxide, or other material having the proper one-way conductance characteristic.

Because of the described continuous direct current energization of the coil 10, the voltage values necessary to actuate the relay contacts 11 are greatly reduced. It is therefore necessary to adjust the relay 9 or to add resistance in series with the relay coil 10 in order to cause the starting circuit of the motor to be opened at the same motor speed as in cases where the invention is not used. The resistance may be incorporated in the coil itself, as by increasing the number of turns, or added in the form of a fixed or variable resistor.

Assuming, for the particular filter capacitor used, that sufficient resistance has been added to increase the pick-up voltage to 150 volts, as in the former illustration wherein the invention was not employed, the seal-in and drop-out voltages will not be the same as their former values of 70 and 45 volts, respectively. Instead, the seal-in voltage will be decreased to approximately 50 volts and the drop-out value as low as 10 volts. This voltage spread, with respect to the pick-up value, is a result of the disproportionately increased effectiveness of rectification at lower voltages as distinguished from the higher voltage values.

For the great majority of motors, the substantial decrease in seal-in voltage under the invention is sufficient to prevent all possibility of relay contact fluttering. Thus, in the example, if the voltage induced in the starting winding 7 is 65 volts when the resultant of the induced and line derived voltage is the 150 volt pick-up value, there will be an excess of 15 volts over the seal-in voltage necessary to prevent the contacts 11 from reclosing once they have opened initially.

In addition to their function of eliminating relay contact fluttering, the rectifier and filter capacitor are beneficial in the prevention of contact heating when the motor is operating cyclically. Cyclic operation occurs when the load is sufficiently great to stop the motor when only the running winding is in use, but insufficient to prevent substantially full speed operation when both the running and starting windings are in the line circuit and producing torque. The motor thus increases in speed until the relay 9 picks up and opens the starting circuit, after which the speed is reduced until the induced voltage reaches the drop-out value and the contacts 11 are allowed to close and cut in the starting winding for repetition of the cycle.

When the drop-out value is relatively high, the time interval between pick-up and drop-out will be short and the contacts 11 will open and close frequently and tend to overheat. The substantial change in the drop-out voltage under the present invention, illustrated in the example as a 35 volt decrease, greatly increases the time interval between pick-up and drop-out and allows the contacts to have a relatively long cooling period. The degree of contact heating is therefore substantially diminished and the possibility of excessive contact wear is decreased accordingly.

Although the use of a single half wave rectifier and a filter capacitor is probably the simplest and most inexpensive means of eliminating relay contact fluttering, it would be possible to

achieve substantially the same results by using other rectifier circuits. A relatively expensive full wave bridge rectifier, for example, could be used in place of the half wave rectifier 12, in which case the condenser 13 would be unnecessary.

The embodiment of the invention diagrammed in Fig. 2 illustrates a method of achieving full wave rectification without the necessity of using the usual bridge combination of four half wave rectifiers. In this embodiment, one side of the relay coil 10 is connected to the center of the starting winding 7 and the other side of coil 10 is connected to a lead 14 which extends between a pair of opposed half wave rectifiers 15 and 16. The rectifiers 15 and 16 are then connected, respectively, to opposite ends of the starting winding 7, so that the coil 10 is arranged across a bridge circuit comprising the segments of the winding 7 and the rectifiers 15 and 16.

The effect of this arrangement is to cause a direct current to flow through the coil 10 from one or the other of the segments of winding 7 and the associated rectifier 15 or 16. During the first half cycle of the voltage wave in the winding 7, the rectifier 16 will be operative to block the flow of current but the rectifier 15 will permit current to flow through the relay coil in a certain direction. During the second half cycle the action is reversed, with the rectifier 16 permitting current to flow through coil 10 in the same direction as during the first half cycle. The resulting continuous flow of direct current in the coil reduces the voltage values necessary to actuate the contacts 11 and operates to eliminate fluttering in the same manner as was described in connection with the first embodiment of the invention.

Due to the fact that the coil 10 is connected to the center of the starting winding 7, it will be subject to only half of the voltage impressed upon or induced in said winding. It may therefore be unnecessary to adjust the coil 10 or the resistance of the coil circuit in order to cause the relay to pick up and open contacts 11 at substantially the same voltage and motor speed as in motor circuits not employing the invention.

It maybe desirable, in certain cases, to connect a capacitor across the relay coil 10. The capacitor, although not necessary to the invention, has the effect of eliminating the possibility of hum in the relay 9.

The circuits described in connection with the embodiments of the invention afford simple means of eliminating the relay contact fluttering which frequently occurs when the relay coil is connected across the starting winding of the motor instead of across the series combination of the starting winding and the relay contacts. The invention involves the use of standard circuit elements which may be wired into a single phase motor circuit with a minimum of time and effort. The cost of applying the invention to a motor is therefore very small, especially in view of the decreased relay contact wear and the improved performance of the motor.

Various embodiments of the invention may be employed within the scope of the accompanying claims.

I claim:

1. In a rectifier system for use with a single phase motor having a running circuit and a parallel connected starting circuit, a relay connected for energization by the starting winding of said starting circuit and operable to open said start-

ing circuit as running speed is approached, and a rectifier connected in the circuit of said relay to rectify the current flowing therethrough and increase the differential between the pick-up and seal-in voltages thereof.

2. In a rectifier system for use with a single phase motor having a running circuit, a parallel connected starting circuit, and a relay connected across the starting winding of said starting circuit to open and close said starting circuit as the motor accelerates to and decelerates from running speed, respectively, a rectifier arranged in series with said relay across said starting winding to rectify the current flowing through said relay and increase the differential between the pick-up and seal-in voltages thereof.

3. In a rectifier system for use with a single phase motor having a running circuit, a parallel connected starting circuit, and a relay connected across the starting winding of said starting circuit to open and close said starting circuit as the motor accelerates to and decelerates from running speed, respectively, a rectifier arranged in series with said relay to rectify the current flowing therethrough, and a capacitor shunted across said relay to maintain the energization thereof during intervals of diminished current flow from said rectifier, said rectifier and said capacitor cooperating to cause continuous direct current energization of said relay and thus to increase the differential between the pick-up and seal-in voltages thereof.

4. In a circuit for use with a single phase motor having a running winding and a parallel connected starting winding, a pair of opposed half wave rectifiers connected in series with each other across said starting winding, a relay coil connected at one end to the center of said starting winding and at the other end to the electrical connection between said rectifiers, and a pair of normally closed relay contacts arranged in series with said starting winding and operably associated with said relay coil to open the starting circuit of said motor as running speed is approached, said rectifiers cooperating to effect continuous direct current energization of said relay coil and increase the differential between the pick-up and seal-in voltages thereof to prevent fluttering of said relay contacts.

5. A single phase motor adapted to be connected to a source of alternating current and comprising a rotor, a running winding, a starting winding connected in parallel with said running winding, a reactive element connected to shift the phase of the current in said starting winding with respect to the current in said running winding, a relay coil connected across said starting winding and energized by voltage induced in said starting winding from said rotor, a relay contact arranged in the circuit of said starting winding and operable when actuated by said relay coil as the speed of said rotor increases to disconnect said starting winding and said relay coil from said source of current of said motor, and a rectifier connected in the circuit of said relay coil to rectify the current flowing therethrough and increase the differential between the pick-up and seal-in voltages thereof.

6. A single phase motor adapted to be connected to a source of alternating current and comprising a rotor, a running winding, a starting winding connected in parallel with said running winding, a reactive element connected to shift the phase of the current in said starting winding with respect to the current in said run-

ning winding, a relay coil connected across said starting winding and energized by voltage induced in said starting winding from said rotor, a relay contact arranged in series with said starting winding and operable when actuated by said relay coil as the speed of said rotor increases to disconnect said starting winding and said relay coil from said source of current of said motor, a rectifier connected in the circuit of said relay coil to rectify the current flowing therethrough, and a capacitor shunted across said relay coil to maintain the energization thereof during intervals of diminished current flow from said rectifier, said rectifier and said capacitor cooperating to cause continuous direct current energization of said relay coil and increase the differential between the pick-up and seal-in voltages thereof.

7. A single phase motor adapted to be connected to a source of alternating current and comprising a rotor, a running winding, a starting winding connected in parallel relation with said running winding, a reactive element connected to shift the phase of the current in said starting winding with respect to the current in said running winding, a pair of opposed half-wave rectifiers connected in series with each other and in

parallel with said starting winding, a relay coil connected at one end to the center of said starting winding and at the other end to the electrical connection between said rectifiers, and a pair of normally closed relay contacts arranged in the circuit of said starting winding and operable when actuated by said relay coil as the speed of said rotor increases to disconnect said starting winding and said relay coil from said source of current of said motor, said rectifiers cooperating to effect continuous direct current energization of said relay coil and increase the differential between the pick-up and seal-in voltages thereof to prevent fluttering of said relay contacts.
